UNITED STATES PATENT OFFICE.

MORTON VAN METER, OF CADILLAC, MICHIGAN.

VEHICLE WHEEL.

Application filed September 7, 1920. Serial No. 408,527.

To all whom it may concern:

Be it known that I, MORTON VAN METER, a citizen of the United States, residing at Cadillac, in the county of Wexford, State 5 of Michigan, have invented a certain new and useful Improvement in Vehicle Wheels, and declare the following to be a full, clear, and exact description of the same, such as will enable others skilled in the art to which 10 it pertains to make and use the same, reference being had to the accompanying drawings, which form a part of this specification.

This invention relates to vehicle wheels, 15 and the principal object of the invention is to provide a wire wheel construction of such character as to permit its use with a wood wheel hub. There are many wood wheels in use and by the construction hereinafter 20 more fully described the hubs of these wood wheels may be utilized by replacing the rim and spokes of the wood wheels by a wire wheel construction. Another object of the invention is to secure a wire wheel 25 construction that is comparatively inexpensive in character adapted to utilize a hub of the ordinary construction used with a wood wheel and to secure a light and resili- 30 ent wheel. A further object of the invention is to provide a wire wheel of a character adapted to replace the spokes and rim of a wood wheel and to secure a construction permitting the use of spokes of considerable 35 angularity to the center plane of the rim. An additional object of this invention is to 40 provide a readily demountable wire wheel in which the usual inner and outer hub members are dispensed with thus materially reducing the cost of manufacture. These 45 and other objects and several novel features of the invention are hereinafter more fully described and claimed, and the preferred form of construction of a wheel embodying my invention is shown in the accompanying drawing which is a cross section of my improved wheel showing the hub in elevation.

With the usual demountable wheels as heretofore manufactured, there is an inner hub member and an outer hub member 50 keyed together and the machining of the parts is somewhat expensive and also the parts are oftentimes difficult to disassemble due to the close fitting relationship of the same whereby rust between surfaces in contact tends to "freeze" the same together. With the construction hereinafter more

fully described, I am able to use a hub of the same character now used with an ordinary wood wheel hub having flanges between which, in the wood wheel structure, the inner spoke ends are secured. Such a hub is shown in the drawing which has a portion 1 provided with an outwardly extending flange 2 integral therewith and on a reduced portion 3 of the hub is a longitudinally movable flange 4 having a small hub fitting the said portion 3. In place of the wood spokes which ordinarily in the construction of a wood wheel are held between these flanges, I provide a disc member 5 preferably of 70 wood apertured to receive the flange bolts 6 of which there are several. These bolts pass through both the integral and movable flanges 2 and 4 and securely retain the disc 5 in position to rotate therewith. The disc 75 is centrally apertured as will be noted in the drawing, to permit introduction over the reduced portion 3 of the hub. This disc member may be made of any desired material preferably of wood and when made of 80 wood a metal ring member 7 should be shrunk or secured about the periphery thereof.

The wire wheel member consists of a rim 8 which may be of any approved type, either 85 what is known as "clincher" or "straight-side" or any other desired design, having seats for the several sets of spokes which tie the rim to what I have termed the auxiliary hub 9. This auxiliary hub 9, which 90 may be a cast hub or made of sheet metal of sufficient strength for the purpose, is provided with an annular recess 10, the peripheral wall of which seats over the periphery of the disc 5 or if a wooden disc 95 engages over the peripheral metal band 7 of the disc. This flange is apertured to receive the spoke ends substantially as shown and is secured to the disc at 5 by means of the bolts 11 extending through the disc 100 member 5 and through apertures provided in the side walls of the recessed portion 10. The hub member 9 extends outwardly from this portion 10 substantially in the shape of a truncated cone and shaped at the truncated end in any desired manner in simulation of an ordinary hub as indicated at 12. This portion may be apertured to receive the spoke ends of the sets of spokes 13 which are at an extreme angle to the center 110 plane of the wheel and giving the same great strength being in position to effectual-

ly resist side strain imposed on the wheel in use. While not here shown, the truncated end of the cone portion 9 may be provided with a cap or plate of any desired character to close the aperture 14 therein through which the hub end is exposed. This aperture 14 permits the introduction of a wrench to remove the hub member 1 from the spindle of the axle (not here shown.)

10 With the construction above outlined, a wire wheel that has the rim portion and tread in the same relationship to the hub as in the ordinary wood wheel construction is secured. Also the wire wheel is readily demountable by removal of the nuts of the bolt 11, whereupon the wheel is demounted from the disc 5. This is readily accomplished as there are no keyed parts requiring considerable force to demount the same as with

15 former constructions where inner and outer hub members are utilized. With the construction above outlined including a hub similar to that of the usual wood wheel, I have secured a demountable wheel without

20 the use of the ordinary inner hub which requires to be machined and this results in low manufacturing cost as the pressed steel or cast hub 9 requires no particular expensive machining and with this construction

25 this type of wheel may be universally used as the same is adapted for use with any wood hub simply by varying the bore of the member 5 and spacing of the apertures for the bolts 6 to correspond with the type of hub utilized.

By this construction as above outlined the locking device heretofore necessarily utilized with demountable wheels is dispensed with as the bolts by means of which the auxiliary hub 9 is secured to the disc member 5, securely hold the parts in the assembled relationship without possibility of the demountable portion becoming loosened in use as with the locking type of demountable hubs heretofore used. While I have shown the rim and auxiliary hub as connected by three sets of spokes it is to be understood that the spoke arrangement may be of any desired character without departing from the spirit of this invention.

Having thus fully described my invention, what I claim is—

1. In a vehicle wheel the combination with a hub having a fixed lateral flange and a similar flange movable longitudinally of the hub, of a wood disc centrally apertured to receive the hub and adapted to be secured between the said flanges, an auxiliary hub having a portion parallel with the plane of the disc and a portion at a right angle thereto fitting over the periphery of the disc, and bolts extending between the disc and the said parallel portion of the auxiliary hub detachably securing the auxiliary hub to the

wood disc, a rim and a series of spokes extending between the rim and auxiliary hub. 65

2. In a vehicle wheel, a hub member having an inner integral and an outer detachable flange, a disc like member centrally apertured to pass over the hub, means for securing the disc between the said flanges, an auxiliary hub having a portion parallel with the face of the disc and a portion at a right angle thereto fitting over the periphery of the disc, the terminal of the said right angle portion having seats for spokes, said auxiliary hub also having an outwardly extending portion covering the main hub and provided at the outer end with seats for spokes, means for securing the auxiliary hub 70 to the disc, a rim and spokes extending between the rim and the said seats of the auxiliary hub.

3. In a vehicle wheel the combination with a hub having spaced flanges, the outermost flange being detachable, of a disc like member centrally apertured to pass longitudinally onto the hub member, the disc member being secured between the said flanges, an auxiliary hub substantially cone shaped in 85 general form and having a base portion fitting over the disc member, a portion thereof lying in side contact with the disc member, a series of bolts for detachably connecting the auxiliary member to the disc like member, a rim, and a series of spokes extending between the rim and the auxiliary hub, a portion of said series of spokes extending to the outer small end of the auxiliary hub and another series extending to 90 the base of the auxiliary hub.

4. In a vehicle wheel, the combination with a hub having spaced flanges, of a disk secured between the flanges, an auxiliary hub having a portion engaging the side of the disk and a portion at a right angle thereto fitting over the periphery, bolts extending through the disk and portion of the auxiliary hub detachably securing the hub to the disk, a rim and spokes extending between the auxiliary hub and rim, the structure upon assembly positioning the center plane of the wheel practically coinciding with the center plane of the disk. 105

5. In a vehicle wheel the combination with a hub having spaced flanges, of a disk secured between the flanges, an auxiliary hub having one end formed for detachable connection with the disk and an outwardly extending portion covering the end of the hub, a rim and spokes extending between the rim and both ends of the auxiliary hub positioning the center plane of the wheel practically coinciding with the center plane of the disk. 115

In testimony whereof, I sign this specification.

MORTON VAN METER.
